Primary Examiner—Terry A. Wallace(74) *Attorney, Agent, or Firm*—Pennie & Edmonds LLP(57) **CLAIM**

The ornamental design for a beverage container lid, as shown and described.

DESCRIPTION

FIG. 1 is a perspective view of a beverage container lid according to the present invention;
 FIG. 2 is a front view thereof;
 FIG. 3 is a rear view thereof;
 FIG. 4 is a left side view thereof, the right side view being a mirror image thereof;
 FIG. 5 is a top view thereof; and,
 FIG. 6 is a perspective view thereof, with a beverage container shown in broken lines and, therefore, not constituting part of the claimed design.
 All broken lines in the above figures are for illustrative purposes only and form no part of the claimed design.
